UNITED STATES PATENT OFFICE.

JOHN T. TICE, OF WEST POINT, GEORGIA.

RACK.

1,335,621.

Specification of Letters Patent. Patented Mar. 30, 1920.

Application filed October 17, 1919. Serial No. 331,270.

To all whom it may concern:

Be it known that I, JOHN T. TICE, a citizen of the United States, residing at West Point, in the county of Troup and State of Georgia, have invented new and useful Improvements in Racks, of which the following is a specification.

My present invention has reference to calendar racks for picking machines in tile mills and is of a substantially similar nature to my pending application Serial No. 298,156, filed May 19, 1919.

The improvement contemplates the employment of a calendar rack having at its upper end a laterally extending fixed head portion to which is pivotally secured a hollow movable head portion, the latter having a depression or pocket to receive the lap pin of a picking machine and anti-frictional rollers which contact with the said pin, the fixed head being provided with a pivoted arched member that contacts with the outer face or top of the movable head for retaining the movable head in proper position on the fixed head, the said arched member being held in such contacting engagement with the movable head through the medium of a fragile element connected to both the arched member and to the fixed head, the construction being such that when excessive pressure is exerted by the lap pin against the pivoted head the fragile member will become broken, permitting the pivoted head member and the arched contact member being swung rearwardly upon their respective pivots, so that no injury, other than the breakage of the fragile member will result to either the calendar rack or to the parts of the picking machine which might otherwise be seriously injured and which, incident to the flying parts caused by such injuries might result seriously to the operator or to others in close proximity to the machine.

Other objects and advantages will present themselves as the nature of the invention is more fully disclosed, reference being had to the accompanying drawings, in which:

Figure 1 is a side elevation of the improvement.

Fig. 2 is a front elevation thereof.

Fig. 3 is a sectional view approximately on the line 3—3 of Fig. 2.

Fig. 4 is a perspective view of the movable member of the head.

Fig. 5 is a perspective view of the upper portion of the rack having the fixed head.

Fig. 6 is a perspective view of the arched member which is pivoted to the outer end of the fixed member of the head and which engages with the movable member of the head to hold the same in fixed position on the fixed member of the head.

Fig. 7 is a perspective view of the fragile connecting member between the arched contact member and the fixed member or section of the head.

My improved calendar rack includes the usual shank 10 having its outer edge provided with the usual teeth 11. The shank at its upper end is integrally formed with a head section 12. This head is substantially V-shaped in side elevation, the lower wall of which being arranged at a right angle with respect to the shank, the front wall being preferably slightly dished, and the upper or rear wall being arranged at a right angle with respect to the shank, the front wall being preferably slightly dished, and the upper or rear wall being disposed substantially at a right angle with respect to the lower wall. The fixed head 12 is of a greater thickness than the shank 10, and the upper or rear wall thereof, indicated for distinction by the numeral 13 has at its outer end upstanding ears 14 which are flush with the sides of the head section. In addition to this, the said top or rear wall 13 adjacent to the front concaved wall 15 of the head section, is provided with additional upstanding ears 16, the last mentioned pair of ears being of a less length than the first mentioned pair of ears. The fixed head section, it will be noted, projects laterally from the shank in a direction beyond the edge thereof opposite that provided with the teeth 11, which is an important feature of the invention, inasmuch as the weight of the said head will resist the pressure exerted by the toothed wheels on the picking machine which engage between the teeth and consequently tend to prevent an outward or lateral swinging of the calendar rack.

The movable head section for the calendar rack is broadly indicated by the numeral 17, the same including an upper solid body portion 18 which is provided with depending sides or flange portions 19 that extend a suitable distance beyond the rear of

the body. It will be noted, by reference to the drawings that the rear portion of the movable head is substantially V-shaped in side elevation, corresponding in shape to 5 that of the fixed head section. The movable head section has its upper corner rounded and its outer face straight. The side members or flanges are so spaced as to be arranged over the sides of the fixed head section 10 and the said sides are pivotally connected to the outer end of the said fixed head section, as indicated by the numerals 20—20. The lower edge of the sides 19 are disposed flush with the lower straight face of the 15 fixed head, and the shank 10 at its juncture with the fixed head is provided with outstanding members or lugs 21 which, contacting with the lower edges of the side members 19 limit the swinging of the movable head section downward with respect to the 20 fixed head section. The side members outward of the shank are provided with inwardly extending rounded depressions 22 arranged in opposite alinement and the 25 lower corners of the said sides 19 are rounded as at 23. These last mentioned rounded portions may be termed lips, and between these said lips there is arranged an anti-frictional roller 24 that has its ends provided with trunnions that find bearings in 30 openings in the lips. A similar roller 25 having its ends also provided with trunnions received in suitable bearing openings in the sides 19 is arranged to have its lower 35 periphery project slightly in the depressions 22. The ends of the lap pin around which the cotton lap is wound find bearings in the depressions 22 and are contacted by the anti-frictional rollers 24 and 25, it being understood that 40 two of such racks are employed, and as the construction and arrangement of the calendar racks on a spinning machine and the construction and coöperation of the lap pins 45 with the calendar rack heads are likewise so well known in the art, the illustration thereof of has not been deemed necessary.

Pivotal secured, as at 26, between the ears 14 and the fixed head section is an 50 arched member 27 that has its outer end 28 flat to provide a firm contacting surface with the rear angle wall of the body portion 18 of the movable head section. The arched member 27 is provided with depending ears 55 29 disposed opposite the ears 16 on the fixed head section. Between the ears 29 and between the ears 16 there are pivoted the ends of a fragile element 30 that secures the arched member 27 in fixed position on the 60 fixed member of the head and in proper contacting position with the movable member of the head. The member 30, in order to render the same more fragile is centrally reduced, so that the same provides a recipro- 65 catory neck portion 31 that connects the

cross sectionally rounded end portions 32, the said end portions being of a length sufficient to be received snugly between the ears 16 and 29 and receiving the pivots that pass through the said ears.

The weighted portion of the movable head section being disposed outwardly of the fixed head section tends to counter-balance the weight of the said fixed head section and the elements connected therewith so that the 75 calendar rack will be perfectly balanced and consequently prevent the bending or breaking of the lap pin of the calendar head and prevent the lap pin from bearing outward or hanging on the main frame of the picker 80 machine.

From the foregoing description, when taken in connection with the drawings, it will be apparent to those skilled in the art to which this invention appertains that an 85 excessive pressure of the lap pin against its bearings in the movable head section of the calendar rack will cause the breakage of the fragile element 30, thus relieving the arched contact member from its fixed engagement with the fixed head section, and permitting the movable head section to swing rearwardly on the fixed head section, so that no injury, other than the breakage 90 of the fragile element will result to either 95 the calendar rack or to the parts of the machine to which it is connected. When the excess of pressure has been removed or relieved the pivoted or movable section of the head of the calendar rack may be swung to 100 operative position and a new fragile element may connect the arched contact member for the pivoted head section to the fixed head section, and the working of the machine will be only slightly delayed. Other 105 advantages of a calendar rack constructed with a fixed and movable head section have been fully set forth in my referred to co-pending application Serial No. 298,156, filed May 19, 1919, so that a detailed enumeration thereof 110 is not here deemed necessary.

Having thus described the invention, what is claimed as new, is:—

1. A calendar rack having a laterally extending fixed head portion and a movable head section pivotally secured to the fixed head section and projecting in an opposite direction from said fixed head section, a pivoted member on the fixed head section contacting with the movable head section 115 for retaining the latter in one position, and a breakable element between said pivoted element and the fixed head section for retaining the latter in engagement with the movable head section except when an excessive 120 pressure is exerted upon the latter in one direction.

2. A calendar rack having a pivoted head section at the upper end thereof, a pivoted overlying element contacting with the sec- 130

tion for holding the section in one position on the rack, and a breakable element connected with said overlying element and the rack for holding said first mentioned element in contacting engagement with the pivoted head section.

3. A calendar rack having a laterally extending fixed head section, a hollow head section providing a bearing pivotally secured to the fixed head section and extending in an opposite direction therefrom, a pivoted element on the fixed head section contacting with the movable head section for holding the same in one position with respect to the fixed head section, and a fragile element connected to the pivoted element and the fixed head section for holding the said first mentioned element in contacting engagement with the pivoted head section.
- 20 4. A calendar rack having a laterally extending substantially V-shaped head pro-

vided with spaced pairs of ears upon the outer and upper portion thereof, a movable head section including a body having depending sides which extend to the rear thereof and straddle the fixed head and are pivotally secured to the said fixed head, said depending sides, outward of the rack having alining curved depressions providing a bearing opening, anti-frictional elements carried by the sides and projecting into the bearing opening, an arched member pivotally secured to the rear pairs of ears on the fixed head section and contacting with the upper face of the pivoted head section, depending ears upon the arched member, and a fragile element pivoted between these ears and the second pair of ears on the fixed head for holding the arched member in contacting engagement with the pivoted head.

In testimony whereof I affix my signature.
JOHN T. TICE.
